UNITED STATES PATENT OFFICE

EDSELL T. BLEECKER, OF PUEBLO, COLORADO, ASSIGNOR TO ALBERT B. CHRISTY, OF COLORADO SPRINGS, COLORADO

MASKING MACHINE

Application filed December 23, 1929. Serial No. 416,106.

My invention relates to masking machines shown generally in my co-pending application Serial No. 314,300. An object of the present invention is to simplify the masking machine shown in said application.

Another object is to provide means for bringing each of the masks comprised in the machine into contact with an object being masked, by lever means operating independently upon each mask.

A further object is to provide means for bringing a mask down on top of an object being masked, and to move the mask out of the path of the object so that the latter may be removed from the machine when finished.

Still other objects reside in details of construction and in novel combinations and arrangements of parts, which will more fully appear in the course of the following description.

In the drawings, like reference characters designate similar parts in the several views.

Figure 1 is a side elevation of a machine embodying the features of the present invention.

Figure 2 is an end elevation of the machine shown in Figure 1, looking in the direction of the arrow "A".

Figure 3 is a broken section taken along the lower part of the line 3—3 of Figure 2.

Figure 4 is a broken section taken on the line 4—4 of Figure 2.

Referring more specifically to the drawings, the reference numerals 5 designate shoes in which feet 6 of the machine rest. The feet support a rectangular, flanged base plate 7 upon which legs 8 are mounted for the support of a bed 9 for an object to be masked, such as a box.

Bolted to the under-side of the base plate 7 and projecting from the middle portions of the four sides are pairs of arms 12 held rigidly together by bolts 13 and spacing sleeves 14 on the bolt and between the arms.

Pairs of upstanding levers are fulcrumed at the ends of the arms 12. Levers 15 at the ends of the machine are fulcrumed, as shown at 16, and levers 17 at the sides of the machine are fulcrumed as shown at 18. The

pairs of levers 15 are held together by a series of bolts 19 in spacing sleeves 20, and the levers 17 are held together by a series of bolts 21 in spacing sleeves 22.

The end levers 15 carry springs 23 at 55 their upper ends for the support of end masks 24. All of the masks mentioned in this specification are cupped on the side facing the object being masked, so that any ornament or inequality in the middle portion 60 of any of the faces of the masked object will not interfere with the snug fit of the masks on said faces.

The springs 23 are mounted at the ends of the levers 15 through the intermediary 65 of bolts 25 that extend through apertured plates 26 at either side of the levers and through cups 27 for the ends of the springs 23.

All of the springs comprised in this invention provide resilient, flexible and contractible supports for the masks.

The side levers 17 carry springs 28 attached at one end to the upper portions of the levers by bolts 29 extending through 75 apertured plates 30 on either side of the levers and through cups 31, as in the case of the end levers. Side masks 32 for the machine are mounted at the opposite end of the springs.

The springs 31 are fastened to the levers 17 at a short distance from the upper ends thereof. Fulcrumed at the ends of the levers 17 by means of bolts 33 are pairs of levers 34 which carry springs 35. At the outer ends of 85 the springs 35 are mounted masks 36 for the top of the box. The box to be masked is indicated in Figures 1 and 2 in dotted lines as shown at 37.

The springs 35 are fastened at one end of 90 the levers 34 by bolts 38, apertured plates 39 and cups 40, as hereinbefore described in connection with the other springs. Bolts 41 and spacing sleeves 42 are employed for holding the levers 34 rigidly in spaced relation to 95 each other.

Extending between the bed 9 and the base plate 7 is an upright shaft 43 upon which is mounted a sliding sleeve 44. An operating lever 48 for the machine has a handle 45 and

a yoke 46 pivotally connected with sleeve 44 at opposite sides by bolts 47. The end of the lever opposite to the handle 45 is fulcrumed at 50 on a support 49 pivotally suspended from the bed 9.

5 Supports 51 are mounted at the middle of the ends of the base plate 7. They carry links 52 which are pivotally connected with links 53 on the sliding sleeve 44. The pivotal connections between the links 52 and 53 are bolts 54. These bolts also pivotally connect the links 53 with links 55 on the levers 15. The links 53 and 55 form toggles for the lateral movement of the levers 15.

10 15 Supports 56 are mounted at the middle of the sides of the base plate 7. Levers 57 on the supports are pivotally connected at one end to rods 58 which in turn are pivotally connected with the levers 34. The other end of the levers 57 are connected with links 59 on the sliding sleeve 44. The side levers 17 are connected with the links 59 by intermediary links 60.

20 25 The operation of the machine is as follows: By raising the operating lever 48 to its extreme upward position, the masks are drawn outward. A box or other object may then be placed in the bed 9. By lowering the lever 48, the masks are moved into contact with the box. The springs resiliently hold the masks in position and take up any play and absorb minor mal-adjustments of the machine.

30 35 The up and down movement of the lever 48 moves the sliding sleeve 44 concurrently. The links 53 and 59 are suspended from said sleeve. The links 53 operate the end levers 15 through the links 55, and the links 59 operate the side levers 17 through the links 60 and the top levers 34 through the levers 57 and rods 58.

40 45 Changes may be made in the details of construction and arrangement without departing from the spirit of the invention.

45 What I claim and desire to secure by Letters Patent is:

1. In a masking machine, a bed for an object to be masked, a lever, a second lever fulcrumed on said lever, masks on the levers, and operating means connected to move the levers to a position in which the masks thereon contact with an object in the bed.

50 55 60 65 2. In a masking machine, a lever, a second lever fulcrumed on said lever, masks on the levers, and an element connected to transmit independent movement to each of the levers, and mechanism for the operation of the element.

65 70 75 80 85 90 95 100 105 110 115 120 125 130 3. In a masking machine, a bed for an object to be masked, a lever, a mask on the lever, and means connected to move the mask into contact with an object in the bed, comprising a sliding member, a second lever connected with the first-mentioned lever and with

the sliding member, and an operating lever connected with the sliding member.

4. In a masking machine, a bed for an object to be masked, levers, end masks and side masks on the levers, and means to move the levers inward or outward with respect to the bed, comprising a sliding member having link and lever connections with the levers carrying the masks, and an operating lever connected with the sliding member.

5. In a masking machine, a bed for an object to be masked, a mask, a lever carrying the mask, a toggle joint to move the lever inward or outward with respect to the bed, and means to operate the toggle.

6. In a masking machine, a bed for an object to be masked, a mask, a lever carrying the mask, a toggle joint to move the lever inward or outward with respect to the bed, means to operate the toggle including a sliding member connected with the toggle, and an operating lever connected with the sliding member.

7. In a masking machine, masks, levers carrying the masks, a sliding member, a toggle connecting one of the levers with the sliding member, a connecting rod and a lever connecting another of said levers with the sliding member, and an operating lever for the sliding member.

8. In a masking machine, a lever, a second lever fulcrumed on the first lever, masks on the levers, a sliding member, a toggle connecting the first-mentioned lever with the sliding member, a connecting rod and a lever connecting the second lever with the sliding member, and an operating lever for the sliding member.

9. In a masking machine, a bed for an object to be masked, masks, arms carrying the masks, a sliding member, means connecting the sliding member with the arms to move the latter inward or outward with respect to the bed, a support on the under side of the bed, and an operating lever for the sliding member fulcrumed on the support.

In testimony whereof I have affixed my signature.

EDSELL T. BLEECKER.
